[57]

ABSTRACT

This display comprises a pole carrying a motor at its upper end, having an upwardly extending drive shaft on which is mounted means to facilitate the installation of a display member in the field and to support and stabilize the weight of the display member more evenly as opposed to the conventional "U" bracket. The display member is simply lifted over the support unit, and lowered onto a conical portion of an adaptor for self-centering of the display member which finally rests on a flange surrounding the base of said conical portion.

FIG. 1

FIG. 2

FIG. 5

FIG. 3

MOTOR OPERATED POLE SUPPORTED MOTION DISPLAY

This invention relates to motor operated pole supported motion displays.

An object of this invention is to provide a display of the character described which may be operated by a battery actuated motor or by a motor operated by house current, and which shall accommodate a motor having a flattened drive shaft. In accordance with the invention an adaptor made of plastic has a center hole to receive an upwardly extending flattened motor drive shaft, a conical portion to aid in centering the display, and a flat annular horizontal flange surrounding the base of the cone, on which the display member comes to rest for rotation with said adaptor when the motor is energized.

Another object of this invention is to provide in a display of the character described, a conical adaptor which also has a center hole at its upper end to receive a shaft carry a additional display member to rotate with the first display member.

Still another object of this invention is to provide a strong and durable display of the character described, which shall be relatively inexpensive to manufacture, easy to assemble, and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

FIG. 1 is a vertical view of a display embodying the invention, with parts in cross-section and showing use of a motor operated by house current;

FIG. 2 is a vertical cross-sectional view of the upper end of the pole and the conical adaptor unit illustrating the use of a battery operated motor;

FIG. 3 is a partial perspective exploded view of some of the structure of FIG. 1;

FIG. 4 is a view like FIG. 3, but illustrating a modified construction, and

FIG. 5 is a cross-sectional view taken on line 5—5 of FIG. 2.

Referring now in detail to the drawing, 10 designates a display embodying the invention. The same may comprise a stand 11. Said stand comprises a base 12 on which a tubular pole 13 is fixed. Fitted into the upper end of the pole 13 is a motor 14. Said motor has wings 15 fixed to its outer case, extending over the upper end of the pole. Said motor is fixed to the pole in any suitable manner and has a central upwardly extending drive shaft 17. Said shaft may have a flat surface 18 offset from the axis thereof. Mounted on the upper end of shaft 17 is an adapter 20 made of plastic or any other suitable material. Said adaptor 20 has a hollow conical portion 21 with apex 22 at the top. Extending down from the apex is an axial stem 23 formed with an axial bore or hole 24 having a longitudinal flat surface 25. The upper end of shaft 17 projects into hole 24 and the flat surface 18 of the shaft contact flat surface 25. Thus, when the motor operates, the drive shaft rotates adaptor 20. At the lower end of the conical portion 21 is a downwardly extending cylindrical portion 28, from the lower end of which an annular horizontal flange 29 extends outwardly.

Stem 23 may be connected to the cone 21 by radiating webs 23a.

At the upper end of the apex 22 there is an axial hole 30 which also has a flat, like flat 25. A vertical rod 31 having a flat 32 projects down into hole 30 for rotation with the adaptor 20.

At the upper end of rod 31 is a display member 35 of any suitable design.

In FIG. 1, the motor 14 may be one that is operated by house current. The usual wires 39 for the motor may extend down into tube 13 and may be connected to a switch 40 and

extend, as at 41, from the base and terminate in a plug 42 for insertion in a wall outlet. If desired, the motor 14 may be operated by a battery 50 housed in the pole, as shown in FIG. 2. Multiple batteries may be used and they may be housed in a tube 50a in a circuit such as shown and described in FIG. 2 of my copending application, Ser. No. 23,345 filed Mar. 27, 1970.

Mounted on the adaptor 20 is a display member 55. This display member may be hollow as shown in FIGS. 1 and 3. It may be of square traverse cross-section. Said member 55 may have a top wall 56 formed with a central round hole 57 of a diameter just slightly greater than the outer diameter of cylindrical portion 28 of adaptor 20. The top wall 56 rests on flange 29. Said display member 55 has four vertical side walls 58 and a bottom wall 60. Bottom wall 60 has a center round hole 61 of a diameter greater than the outer diameter of flange 29.

Thus, the display member 55 may be fitted over the adaptor which easily passes through opening 61. The member 55 is then lowered onto the adaptor and centers itself by contact with cone 21 and comes down to rest top wall 56 on flange 29.

If desired, flange 29 may have opening 29a to receive pins 56a attached to wall 56 and projecting therebelow.

The upper display member 35 may have its shaft 31 applied to the adaptor, after the display member 55 is hung. Friction alone will cause the supported member 55 to rotate with the adaptor. However, if desired interengaging pins 56a and holes 29a may additionally be employed.

In FIG. 4, the lower display member 70 is rectangular and has a top wall 71 formed with a rectangular hole 72. The adaptor 73 for this display member has sloping wall portions 74 and a horizontal flange 75 at its base. The top wall 71 centers itself on the sloping walls and rests on the flange. The sloping walls fit into hole 72. Adaptor 73 has a stem 23 with center hole to receive shaft 17 of the motor same as shown in FIG. 2. It also has a top hole 30 to receive shaft 31 same as shown in FIG. 2.

The primary function of the adaptor is to facilitate the installation of display members in the field, and to support and stabilize the weight of the display member more evenly, as opposed to the conventional "U" bracket which necessitates the use of screws or other fasteners, which may require pre-assembly at the factory.

The adaptor fits into a die cut hole in adaptor top former of the display member, and the flange of the adaptor supports the display member.

The assembled display member is simply lifted over the completed support unit whether in motion or stationary, and lowered until the adaptor centers the display which comes to rest on the flange.

The display member 55 may be mounted on the adaptor at any angle about the axis of the latter. The display is supported all around and at a radius from the center. There is a friction fit, and no screws are necessary. The flat in the hole 24 will fit the usual flat shafted drive shafts of small motors such as made by Hanscraft Inc. of 369 Lexington Avenue, New York, N. Y. 10017.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative.

I claim:

1. A display comprising a stand, a motor on the stand, said motor having an upstanding drive shaft, an adaptor removably and non-rotatably mounted on said shaft and having a downwardly and outwardly sloping portion and being formed with an axial downwardly opening hole to receive the upper end of said shaft, said adaptor being formed with a horizontal flange surrounding the sloping portion at the base of said sloping portion, and a display member having a top wall formed with a hole to receive said sloping portion, and resting on said flange.

2. The combination of claim 1, said adaptor having a hole which opens upwardly and is coaxial with said downwardly opening hole, a shaft having its lower end removably and non-rotatably received in said upwardly opening hole, and another display member on said last mentioned shaft.

3. The combination of claim 1, said display member having a bottom wall formed with a hole coaxial with the hole in the top wall thereof and of a size and shape to permit the adaptor to pass said hole in the bottom wall as the top wall is moved down to the adaptor.

4. The combination of claim 1, said sloping portion of the adaptor comprising a cone, and said flange being annular.

5. The combination of claim 1, said flange being formed with one or more openings.

6. The combination of claim 1, said axial downwardly opening hole being formed in a stem extending downwardly from the apex of said sloping portion.

7. The combination of claim 6, said sloping portion being conical and said flange being annular.

8. The combination of claim 7, said adaptor having a cylindrical wall between said conical portion and said annular flange.

9. The combination of claim 8, said adaptor having a hole which opens upwardly and is coaxial with said downwardly opening hole, a shaft having its lower end received in said upwardly opening hole, and another display device mounted on said last mentioned shaft.

10. The combination of claim 9, said first mentioned display member having a bottom wall formed with a hole coaxial with the hole in the top wall thereof and of a size and shape to permit the adaptor to move through said hole in the bottom wall as said bottom wall moves over the adaptor and the top wall moves toward said adaptor.

11. The combination of claim 10, said flange being formed with one or more openings.

12. The combination of claim 1, said hole having a flat and said drive shaft having a flat contacting the flat in the hole.
